COMB OR SAW FOR COTTON BURR
EXTRACTORSAlexander S. Mackenzie, Houston, Tex., assignor,
by mesne assignments, to Elk City Cotton Oil
Company, a corporation of Oklahoma

Application December 14, 1931, Serial No. 581,007

7 Claims. (Cl. 19—63)

The present invention relates to a comb, particularly useful in connection with cotton burr extractors and aims to provide a construction which will possess very important advantages over the common saw-teeth heretofore used on burr extractors and similar machines.

The conventional tooth is of wedge form, for example as disclosed in the patents to Sargent 6,778 of 1849, Coulston 1,346,637 and Stevens 1,031,097, and consequently each tooth acts as a carrying means for the burrs and when they come in contact with the stripper, they are either driven onto the tooth point or torn into such small pieces as to be mixed with the cotton and hence damage the same.

Having in mind these objectionable features of the conventional structure, the present invention provides a tooth, wherein it will be relatively impossible for the burrs to become caught on the teeth points, and wherein they may be easily removed from the teeth points, at the same time eliminating all possibility of tearing or shredding of the burrs into the smaller undesirable pieces.

A further object of the invention is to provide a saw-tooth arrangement wherein the space between the respective teeth will be relatively wide at the entering portion and tapers to a throat which is curved on a radius, the center of which is the adjacent tooth point, whereby the distance between the point of any tooth and the nearest part of an adjacent tooth will be as great or greater than the depth of the tooth.

By reason of this construction, burrs will not wedge in the space between the teeth and if, for any reason, burrs should fall into such portion, they will readily be moved therefrom or rotated out of the space by contact with a stripper, for example, which is either fixed or which travels in the opposite direction.

Referring to the drawing,

Figure 1 is a plan view showing my invention applied.

Figure 2 is a side elevation showing the saw-tooth arrangement and stripper plate, with burrs to be extracted.

Figure 3 is a detail view of the saw-tooth.

In the drawing, the numeral 10 indicates the usual conveyor in a cotton hulling machine 11 and the rotating extractor having the comb 12 on its periphery constructed in accordance with this invention. It will be understood that a plurality of combs are employed which rotate with the extractor cylinder 11 upon the shaft 13.

In Figure 3, I have shown in detail the con-

struction of the teeth of the comb. These teeth will be indicated as a whole at 14 and are preferably integrally constructed, although they may be separately formed as desired.

It is to be observed that each tooth has a relatively short side 15 and a long side 16, the two sides extending angularly toward each other to the tooth edge 17. The edge 17 is flattened, as shown, and is relatively narrow, longitudinally terminating in the point 18.

The space between the teeth is wide between the flattened edges 17 and this distance is reduced toward the throat 19.

The throat 19 is curved as shown and the radius of curvature is that attained by using the point 18 of the adjacent tooth as a center.

It will thus be seen that the tooth has a very wide entering portion defined by the long side 16 and the short side 15 of the adjacent tooth, which merge into the curved throat 19.

The advantages of the several features just described will now be recited.

By employing a tooth having the flattened edge 17, there is eliminated all possibility of the cotton burrs being pierced by the point 18, so as to become permanently impinged upon the tooth point. Such a feature occurs with the prior patents referred to, but with the present construction this difficulty is effectually overcome.

In addition to this feature, moreover, by the provision of the flattened edge 17, I prevent a tearing or such shredding of the burrs and hulls as will cause them to disintegrate into small pieces. By preventing this result, there is no opportunity for small and objectionable particles and pieces of the hulls to become mixed with the cotton and thus spoil and damage the samples.

By providing the wide entering space between the teeth merging into the curved throat 19, I produce a tooth structure wherein the distance between the point of one tooth and the nearest part of the next adjacent tooth will always be as great, if not greater, than the depth of the tooth. The result of this construction is best demonstrated by reference to Figure 2. Here there is shown the stripper plate 20 and the comb 12 which is moving past the same.

The burr indicated at 21 is about to be struck by the stripper plate, having been carried along by the tooth and it will be noted that the tooth does not pierce the burr or hull and in addition that the stripper plate upon striking the burr will simply rotate it out of position in the space between the teeth, due to the configuration defined by the adjacent walls of the teeth and throat.

In other words, the teeth of the present invention are of such construction that when a burr is hit by the tooth point, and carried to the stripper 20, it will be easily removable from the point and 5 from the space between the teeth.

There is no opportunity given for the burrs to become wedged between the teeth or to be so pierced by the tooth points as to become permanently held thereby.

10 Thus, with the present construction, the burr cannot become so driven onto the tooth point as to be permanently held thereby, and should, for any reason, a burr be pierced the configuration of the straight edge 17 cooperating with the configuration 15 of the space between the teeth comprising the wide entering portion and curved throat will cause said burr to be at once dislodged and rotated out of position upon being struck by the stripper plate.

20 The invention may take a variety of forms, all of which are considered to be comprehended within the appended claims.

I claim:

1. A comb for cotton burr extractors comprising spaced teeth, said teeth each having a relatively short flat portion terminating in a point and the space between the respective teeth defining a throat curved on a radius, of which the tooth point is the center, whereby the distance between 30 the point of one tooth and the nearest part of the adjacent tooth is at least as great as the depth of the tooth, and said flattened edge cooperating with said curved throat portion to prevent permanent penetration and impingement of cotton burrs upon the tooth when acted upon by a stripper member.

2. In combination, a comb for cotton burr extractors comprising spaced teeth, each tooth having a relatively short flattened portion terminating in a point and the space between the teeth defining a relatively wide entering portion merging with a throat curved on a radius of which the tooth point is the center, said tooth spaces being defined by a relatively long inclined side and a shorter side of less inclination, which sides merge with the curved throat, and a stripper plate positioned adjacent said comb, said tooth point cooperating with the curved throat to permit a burr that is carried by the tooth, to rotate about the point and be ejected from the tooth through the wide entering portion when acted upon by the stripper plate.

3. A comb for cotton burr extractors comprising spaced teeth, each tooth having a relatively short flattened portion terminating in a point and forming a blunt means for engaging a cotton boll, the space between the teeth defining a relatively wide entering portion merging with a throat curved on a radius of which the tooth point is the center, the distance between the point of each tooth and the nearest part of the next adjacent tooth being at least as great as the depth of the tooth.

4. A comb for cotton burr extractors comprising

spaced teeth, each tooth having a relatively short flattened portion terminating in a point and forming a blunt means for engaging a cotton boll, the space between the teeth defining a relatively wide entering portion merging with a throat curved on a radius of which the tooth point is the center, the distance between the point of each tooth and the nearest part of the next adjacent tooth being at least as great as the depth of the tooth, the said blunt engaging portions of the teeth cooperating with a substantially blunt stripper member to prevent permanent penetration and impingement of cotton burrs upon the tooth, and the configuration of the space between the teeth cooperating with said blunt means to permit burrs and hulls to be readily rotated out of the space between the respective teeth.

5. A saw for use in cotton extracting machines having teeth separated by outwardly-diverging spaces and provided with flat peripheral edges and knife-edge points, the flat edges lying in planes extending substantially at right angles to radii of the circle described by the saw, and the points of the teeth lying in said planes, the width of the space between each two adjacent teeth at the periphery being at least twice that of the width of each tooth at the periphery, and one side of each of said spaces, constituting the rear side of a tooth, being inclined to the vertical at a greater angle than the other side and having a length at least three times the peripheral width of the tooth.

6. A saw for use in cotton extracting machines having teeth separated by outwardly diverging spaces and provided with peripheral edges flattened longitudinally and transversely to provide substantially knife-edge points, the flat edges lying in planes extending substantially at right angles to radii of the circle described by the saw, and the points of the teeth lying in said planes, the width of the space between each two adjacent teeth at the periphery being at least twice that of the width of each tooth at the periphery, and one side of each of said spaces, constituting the rear side of a tooth, being inclined to the vertical at a greater angle than the other side and having a length at least three times the peripheral width of the tooth.

7. In combination, a comb for cotton burr extractors comprising spaced teeth, each tooth having a point and the space between the teeth defining a relatively wide entering portion merging with a throat curved on a radius of which the tooth point is the center, said tooth spaces being defined by a relatively long inclined side and a shorter side of less inclination, which sides merge with the curved throat, and a stripper plate positioned adjacent said comb, said tooth point cooperating with the curved throat to permit a burr that is carried by the tooth, to rotate about the point and be ejected from the tooth through the wide entering portion when acted upon by the stripper plate.

ALEXANDER S. MACKENZIE.
